Office Action issued in related U.S. Appl. No. 29/635,439 dated Feb. 20, 2019.

Primary Examiner — Mitchell I. Siegel(74) *Attorney, Agent, or Firm* — Morgan, Lewis & Bockius LLP(57) **CLAIM**

The ornamental design for a bobbin with wound thread, as shown and described.

DESCRIPTION

FIG. 1 is a perspective view of a bobbin with wound thread showing our new design;

FIG. 2 is an enlarged fragmented view taken from box 2 on FIG. 3.

FIG. 3 is a front elevational view thereof;

FIG. 4 is a top plan view thereof;

FIG. 5 is a left side elevational view thereof;

FIG. 6 is a rear elevational thereof; and,

FIG. 7 is a bottom plan view thereof.

The broken lines shown are included for the purpose of illustrating unclaimed subject matter and forms no part of the claimed design. The dash-dot lines are included as boundary lines and form no part of the claimed design. The dash-dot-dot lines of FIG. 3 are included to show an enlarged area and form no part of the claimed design.

The characteristic feature of the design resides in the shape and configuration of the bobbin with wound thread shown in the solid lines in the drawings.
